United States Patent Office

Des. 188,315
Patented July 5, 1960

188,315

FOOD SERVICE CART

William H. Frick, 850 Euclid Ave., Cleveland, Ohio
Filed Jan. 6, 1959, Ser. No. 54,053

Term of patent 14 years

(Cl. D14—3)

Fig. 1

Fig. 2

Fig. 3

Fig. 4

Fig. 1 is a front perspective view of a food service cart embodying my new design with one cover lid in open position;

Fig. 2 is a fragmentary perspective view in front elevation with both cover lids open;

Fig. 3 is a rear view with both lids closed; and

Fig. 4 is an end view of the design of Fig. 3.
I claim:

The ornamental design for a food service cart, as shown.
